US00D881248S

(12) **United States Design Patent** (10) **Patent No.:** **US D881,248 S**
Monette et al. (45) **Date of Patent:** **** Apr. 14, 2020**

(54) **LUBE ASSEMBLY HOUSING**

(71) Applicant: **Eaton Cummins Automated Transmission Technologies, LLC**, Galesburg, MI (US)

(72) Inventors: **Daniel Alan Monette**, Battle Creek, MI (US); **Joseph Matthew Sullivan**, East Leroy, MI (US)

(73) Assignee: **Eaton Cummins Automated Transmission Technologies, LLC**, Galesburg, MI (US)

(**) Term: **15 Years**

(21) Appl. No.: **29/595,584**

(22) Filed: **Feb. 28, 2017**

(51) LOC (12) Cl. **15-09**

(52) U.S. Cl. **USPC D15/150**

(58) **Field of Classification Search**

USPC D15/150, 151, 152
CPC F16D 13/74; F16D 48/02; F16D 25/12;
F16D 25/14; F16D 25/123; F16D 25/0638; F16D 2048/0221

See application file for complete search history.

CLAIM

The ornamental design for a lube assembly housing, as shown.

DESCRIPTION

FIG. 1 is a front perspective view of our lube assembly housing design;

FIG. 2 is a rear perspective view of the lube assembly housing design;

FIG. 3 is a rear view of the lube assembly housing design;

FIG. 4 is a front view of the lube assembly housing design;

FIG. 5 is a first side view of the lube assembly housing design;

FIG. 6 is a second side view of the lube assembly housing design;

FIG. 7 is a third side view of the lube assembly housing design; and,

FIG. 8 is a fourth side view of the lube assembly housing design.

1 Claim, 6 Drawing Sheets
